UNITED STATES PATENT OFFICE.

OLIVER WILLIAM KETCHUM, OF TORONTO, CANADA.

DESIGN FOR A SHEET-METAL PULLEY.

SPECIFICATION forming part of Design No. 23,476, dated July 17, 1894.

Application filed June 16, 1894. Serial No. 514,809. Term of patent 14 years.

To all whom it may concern:

Be it known that I, OLIVER WILLIAM KETCHUM, a subject of the Queen of Great Britain, residing at the city of Toronto, in the county of York, in the Province of Ontario, Canada, have invented and produced a new and original Design for Sheet-Metal Pulleys, of which the following is a specification, reference being had to the accompanying drawings, forming part thereof.

Figure 1, is a face view of a sheet metal pulley showing my design. Fig. 2, is a sectional view of the pulley.

In both views the hub is shown in dotted lines.

The leading feature of my design consists

in the shape of the web and rim with raised beads throughout the surface of the web and at the edge as shown.

A is the web of the pulley which is provided with annular beads, *a*, and radial beads, *c*, an edge bead, *b*, forming part of the rim, *B*, at the point of juncture of the rim with the web and a bead, *b'*, forming part of the rim, *B*, at the free edge.

What I claim as my invention is—
The design for a sheet metal pulley as herein shown and described.

OLIVER WILLIAM KETCHUM.
